The ornamental design for a controller for linear actuator, as shown and described.

DESCRIPTION

FIG. 1 is a perspective view of a controller for linear actuator showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof; and,

FIG. 9 is third perspective view showing the controller for linear actuator.

The broken lines show portions of a controller for linear actuator and form no part of the claimed design.
